UNITED STATES PATENT OFFICE.

ANDREW RUNSTETLER, OF DAYTON, OHIO, ASSIGNOR TO THE FARMERS FRIEND MANUFACTURING COMPANY, OF SAME PLACE.

CORN-PLANTER.

SPECIFICATION forming part of Letters Patent No. 308,042, dated November 11, 1884.

Application filed May 13, 1884. (No model.)

To all whom it may concern:

Be it known that I, ANDREW RUNSTETLER, a citizen of the United States, and a resident of Dayton, in the county of Montgomery and State of Ohio, have invented certain new and useful Improvements in Corn-Planters, of which the following is a specification.

My invention relates to that class of corn-planters which employ a main frame mounted on ground carrying-wheels, to which is hinged a front runner-frame which is elevated and depressed by lever mechanism.

The object of my invention is, first, to provide a yielding spring-coupling for hinging the lever mechanism (which is pivoted to the main frame) to the runner-frame.

A second object of my invention is to provide improved lever mechanism for depressing the runner-frame by the use of a hand-lever alone or by a combined hand and foot-lever, and to elevate the machine by a foot-lever attached to the hand-lever, so that the hand-lever may be moved by the feet alone or by both the hand and foot of the operator acting together, as circumstances may require, all of which is fully set forth in the description of the accompanying drawings, in which—

Figure 1 is a plan view of my improvement; Fig. 2, a side elevation of the lever and coupling devices; Fig. 3, a front elevation; Fig. 4, a broken rear elevation of the hand-lever and foot-rest; Fig. 5, a section on line $y-y$, Fig. 2; Fig. 6, a front elevation of the coupling-arm. Fig. 7 is a side elevation of the same. Fig. 8 is a perspective view of one of the coupling-brackets.

A A represent the side rails of the main frame; D, the axle on which the ground-wheels are journaled; E, a seat-standard rigidly secured to the axle.

F represents a segmental bracket provided with flanges e for bolting it firmly to axle D. It is preferably centrally attached to the axle, so as to be nearly in line with the center of the runner-frame.

a a represent notches cut in the edge of the segment.

H represents a stud on which is journaled the bell-crank hand-lever J.

b c d represent locking devices attached to

lever J for locking it to the segment F, and in such a manner as to allow the lever to be set in any desired position.

g represents a link for holding the lock out 55 of engagement with the notches a of the segment when the machine is to be used as a yielding planter.

K represents the forward arm of the bell-crank lever J, to the front end of which the runner-frame is coupled.

The lever devices here shown may be hinged to the runner-frame by any form of connecting-rods; but it is here shown as used, by a yielding or spring-coupling connection, which 65 is constructed as follows:

L represent the hounds of the runner-frame, to which the lever mechanism is usually hinged; M, a coupling-link; m, a slot pierced through the shank or arm of said link, n n, gudgeons which journal in bearings N, pierced in coupling-brackets C, of which there are two, one being the counterpart of the other. They are provided with lugs i, between which the hounds L are bolted, so as 75 to form a firm journal-support for the coupling M.

O represents a seat or chair rigidly secured to arm M, on which the lower end of a spiral or coiled spring, P, rests. The forward end 80 of bell-crank lever J is projected through slot m of arm M.

p p represent guide-pins passing through bell-crank arm K, to hold the coupling M in position.

R represents a cap which is pierced with a hole to pass over the arm M, and forms a seat for the upper end of spring P. It is provided with an annular lip or flange, r, so as to form a bearing for spring P. The spring P 90 forces cap R up against the arm K of the bell-crank lever, but it slides freely on the coupling-arm M, so as to allow a yielding movement of the hound L and rear end of runner-frame under the pressure exerted 95 through the bell-crank lever, to hold the runner-frame down to its work.

I do not wish to limit myself to details of construction of yielding coupling devices herein shown for hinging the lifting and depressing lever to the runner-frame, as this yielding spring movement of the runner-frame may be

obtained in very many ways analogous to these devices and still secure the same results. This form of coupling the lifting-lever of the main frame to the runner-frame is very important, as it removes a serious difficulty hitherto experienced in the locking of the runner-frame to the main frame. It prevents the runners from being depressed too deep into the ground in mellow soil. It allows the runner-frame to conform in a great degree to the inequalities of the ground. The spring takes up jolts and jars occasioned by running over varying soil or when striking substances in the ground.

15 B represents a foot-rest and pushing-piece. It is adjustably secured to lever J by means of a set-screw, s , as shown in Fig. 5, so that it may be raised or lowered upon the arm of lever J. This piece B is adapted to be used as 20 means for depressing the runner-frame by the feet of the operator.

In order that the driver may use his feet to lift the runner-frame, either alone or in conjunction with the hand, I provide the supplemental lever S, which is attached to the hand-lever J, preferably near its upper end. It projects through a mortise, T, in the seat-standard, which thus acts as a guard for lever S.

30 t represents a friction-roller journaled at the bottom of mortise T, to allow lever S to slide back and forward freely.

U represents a foot-piece placed on the rear end of lever S, so that the operator may, by 35 applying his weight thereto, elevate or assist in elevating the runner-frame.

I do not wish to limit myself to the exact form of construction of foot-lever S herein set forth.

The seat-standard may be changed in its location and other means used to guide lever S. So, also, the lever may be rigidly secured to lever J, and be made straight instead of curved; but the form here shown I deem the simplest and best. So, also, foot-lever J may be connected to the runner-frame by ordinary connecting mechanism instead of the yielding coupling here shown.

I claim—

1. In combination with the main frame of a corn-planter, a lifting-lever pivoted to the 50 main frame and hinged to the front runner-frame by means of a yielding spring-coupling pivoted to the runner-frame, substantially as herein set forth.

2. The combination, in a corn-planter, of 55 the rear main frame, the front runner-frame pivotally connected with the latter, the lifting-lever pivoted on the main frame, the coupling-arm pivotally connected to the runner-frame and loosely engaging the lever, and a spring 60 acting on the coupling-arm and on the lever, substantially as described.

3. The combination, with the rear main frame and the front runner-frame of a corn-planter, of the hand-lever J, provided with the 65 foot-piece B and the forwardly-extending arm K, and a spring-connection between the arm and the runner-frame, substantially as described.

4. The combination, in a corn-planter, of 70 the rear main frame, the driver's seat, the pivoted hand-lever arranged in advance of the seat and provided with the foot-piece B and projecting arm K, extending forwardly in line with the lever, and a loose connection between the front end of the arm and the runner-frame, substantially as described.

5. In combination with the hand-lever J, the supplemental lever S, projecting rearwardly under the seat of the operator, whereby 80 the hand-lever may be drawn backward by the feet of the operator for operating the runner-frame, substantially as described.

6. In combination with the seat-standard E, mortise T, and foot-lever S, the friction-roller 85 t, for supporting and guiding the lever S, substantially as herein set forth.

In testimony whereof I have hereunto set my hand.

ANDREW RUNSTETLER.
